L. B. SIMONSON

HAIR DRESSING, WASHING, AND SHAMPOOING EQUIPMENT

Filed July 13, 1923

Inventor
Leo B. Simonson
By *John H. Polachek*
Attorney

UNITED STATES PATENT OFFICE.

LEO B. SIMONSON, OF NEW YORK, N. Y.

HAIR DRESSING, WASHING, AND SHAMPOOING EQUIPMENT.

Application filed July 13, 1923. Serial No. 651,285.

To all whom it may concern:

Be it known that I, LEO B. SIMONSON, a citizen of the United States, residing at New York, in the county of New York and

5 State of New York, have invented certain new and useful Improvements in Hair Dressing, Washing, and Shampooing Equipment, of which the following is a specification.

10 This invention has general reference to equipment or accessories for use in hairdressing, manicuring, or other toilet purposes, the invention having for one of its objects the economy of space in equipment.

15 More specifically the invention has for an object the provision of a novel device which comprises a table and mirror arranged as a unit, with the table positioned above a wash basin and capable of being raised when de-

20 sired to permit of access to the latter.

For further comprehension of the invention, and of the objects and advantages thereof, reference will be had to the following description and accompanying 25 drawings, and to the appended claims in which the various novel features of the invention are more particularly set forth.

Fig. 1 of the drawings is a face view of a 30 device embodying the invention.

35 Fig. 2 is a horizontal sectional view taken on the line 2—2 of Fig. 1.

Fig. 3 is a transverse vertical sectional view taken on the line 3—3 of Fig. 1, but with certain parts in the plane of section 35 shown in elevation.

Referring now to the drawings, the reference numeral 10 indicates a wall, which may be the wall of a private apartment, or one of the apartments of a hairdressing establishment, according to the application of the device for private or professional use. Extending up the face of this wall are a pair of stile-posts 11 which are spaced a suitable distance apart and which have 45 grooves such as 12 on their contiguous faces which serve as guides for the frame 12 of a mirror 13. In the wall 10, behind this mirror 13, is a recess 15 for a purpose to be presently set forth. Fixed to and projecting 50 outwardly from the lower crosspiece of the mirror frame 12 is a table element 16. The mirror and table may be counterbalanced by ordinary window weights carried in passages 17 in the posts 11.

55 This table element normally extends over and covers a wash basin 18 of usual construc-

tion, having the drain pipe 19 and overflow pipe 20. This basin may be supported in the usual way by drain pipe 19.

In the present instance the pipes 22 for 60 conducting the hot and cold water to the basin are shown as passing through the side of the latter, the pipes entering the basin from the recess 15, in which they extend upwardly. Individual valves 23 are placed 65 on the pipes so as to control the supply of water to the basin, these valves being located at a suitable height above the basin.

For washing the hair I provide a suitable device in the form of a length of flexible tubing 25 which has a spray nozzle or head 26 on its free end, the other end of this length of tubing being connected to a mixing valve 27, the latter being provided with a handle 28 for manipulation. Branches 75 29 lead to this valve, from the pipes 22. I do not consider it necessary to illustrate in detail the construction of this mixing valve since I may employ any one of the well known types, the particular construction 80 of this valve having no relation to the present invention.

In order to obviate any chance of the table 16 being lowered upon the basin 18 with the water still flowing through any of the 85 discharge pipes above referred to I preferably provide supplemental shut-off valves 32 on the pipes which are automatically opened and closed as the table is raised or lowered. These valves are operated by handles or 90 arms 33 which, when the valves are closed, extend obliquely downward toward the mirror 13, springs such as 34 being connected to these arms to normally hold the valves closed, and to automatically return them to 95 closed position when the table is lowered. Fixed on the lower crosspiece of the mirror frame 12 are two blocks or projections 37 which are adapted to engage the respective 100 valve handles 33 and lift the latter to open the valves when the table and mirror are raised for access to the basin 18. With the provision of these automatically acting valves any chance of the basin flooding with 105 water, by reason of the latter being inadvertently left running when the table is again lowered is obviated, since the valves 32 are closed by the springs 34 when the blocks 37 move away from the arms 33.

To contain various toilet articles and accessories a pair of cupboards 40 are sunk 110 in the wall one at each side of the mirror,

these cupboards being each provided with a suitable number of shelves. The doors 41 of these cupboards are hinged to their contiguous sides, being here shown as hinged to the posts 11, and carry mirrors 42. These doors may be swung to any suitable position desired to provide a triple mirror by means of which back and profile views may be obtained.

10 As will be apparent from the above description, the improved device is compact and space saving, being particularly suitable for the use of professional hairdressers by reason of the economy of space provided.

15 While I have illustrated and described a preferred embodiment of my invention it is to be understood that I do not limit myself to the precise construction herein disclosed, and that various changes and 20 modifications might be made therein without departing from the spirit and scope of the invention as defined in the appended claims.

Having thus described my invention what 25 I claim as new and desire to protect by Letters Patent of the United States is as follows:

1. A device of the class described, adapted to be secured to a wall having a recess formed therein, a pair of vertical guide elements on said wall one on each side of the said recess, a frame slideable in said guide elements, a table fixed to said frame and projecting laterally from the said wall, a 35 washbasin normally covered by said table, said recess containing water pipes for supplying water to said basin, and hand valves for said water pipes located in the recess and accessible by raising the said frame and 40 table.

2. A device of the class described, adapted to be secured to a wall having a recess formed therein, a pair of vertical guide elements on said wall one on each side of the said recess, a frame slideable in said guide elements, a table fixed to said frame and projecting laterally from the said wall, a washbasin normally covered by said table, said recess containing water pipes for supplying 50 water to said basin, and hand valves for said water pipes located in the recess and accessible by raising the said frame and table, and a mirror fixed in the said frame.

3. A device of the class described, adapted 55 to be secured to a wall having a recess formed therein, a pair of vertical guide elements on said wall one on each side of the said recess, a frame slideable in said guide elements, a table fixed to said frame and 60 projecting laterally from the said wall, a washbasin normally covered by said table, said recess containing water pipes for supplying water to said basin, and hand valves

for said water pipes located in the recess and accessible by raising the said frame 65 and table, other valves on said pipes for controlling the flow of water therethrough, and means whereby the said last named valves are automatically opened and closed as the said frame is raised and lowered. 70

4. A device of the class described, adapted to be secured to a wall having a recess formed therein, a pair of vertical guide elements on said wall one on each side of the said recess, a frame slideable in said guide 75 elements, a table fixed to said frame and projecting laterally from the said wall, a washbasin normally covered by said table, said recess containing water pipes for supplying water to said basin, and hand valves 80 for said water pipes located in the recess and accessible by raising the said frame and table, other valves on said pipes for controlling the flow of water therethrough, and means whereby the said last named valves 85 are automatically opened and closed as the said frame is raised and lowered, said means including arms on said valves and projections on said frame adapted to engage and move the said arms. 90

5. A device of the class described, adapted to be secured to a wall having a recess formed therein, a pair of vertical guide elements on said wall one on each side of the said recess, a frame slideable in said guide 95 elements, a table fixed to said frame and projecting laterally from the said wall, a washbasin normally covered by said table, said recess containing water pipes for supplying water to said basin, and hand valves 100 for said water pipes located in the recess and accessible by raising the said frame and table, other valves on said pipes for controlling the flow of water therethrough, and means whereby the said last named valves 105 are automatically opened and closed as the said frame is raised and lowered, said means including arms on said valves and projections on said frame adapted to engage and move the said arms, and springs connected 110 to the said arms for moving the latter oppositely to the said projections.

6. A device of the class described comprising a washbasin, a table extending above the basin, a pair of vertical guide elements, 115 and a frame slideable in said guide elements and having the said table projecting from its lower end, and a mirror fixed in said frame, cupboards at the sides of said guide elements, and hinged doors closing said cupboards, said doors carrying mirrors adapted 120 to cooperate with the first named mirror.

In testimony whereof I have affixed my signature.

LEO B. SIMONSON.
